UNITED STATES PATENT OFFICE.

DAVIS AMBROSE, OF LOUISVILLE, KENTUCKY.

RAIL CLAMP.

1,418,122.

Specification of Letters Patent. Patented May 30, 1922.

Application filed November 12, 1921. Serial No. 514,730.

To all whom it may concern:

Be it known that I, DAVIS AMBROSE, a citizen of the United States, residing at Louisville, in the county of Jefferson and State of Kentucky, have invented new and useful Improvements in Rail Clamps, of which the following is a specification.

My present invention has reference to a rail clamp.

10 My object is to produce a means for connecting the confronting ends of railway rails in which wedging means will be automatically brought into frictional engagement between the base or foot portions of the rails.

15 and a clamping device for the rails.

A further object is to produce a rail clamp which is constructed of two sections shaped to engage with the sides and the base portions of the rails at the meeting ends of contiguous 20 rails, such clamp sections being secured together at the portions thereof which are arranged below the rails and the said lower portions being provided with pockets in which there are arranged wedge members 25 spring influenced in a direction away from each other and whereby vibration of the rails incident to the rolling stock passing thereover will permit of a canting movement of the clamp sections and allow the springs to 30 influence the wedges to force the same into tighter frictional engagement with the clamp sections and with the base of the rails to effect a binding action between the said wedges and the base portions of the rails and a binding 35 action between the portions of the clamp sections which are received in the fishing spaces of the rails so that the rails will be effectively held from sinking or lateral movement but will be afforded the necessary longitudinal movement incident to expansion and 40 contraction.

The foregoing, and other objects which will appear as the nature of the invention is better understood, may be accomplished by 45 a construction, combination and operative association of parts, such as is disclosed by the drawings which accompany and which form part of this specification.

In the drawings:

50 Figure 1 is a side elevation illustrating the application of the improvement.

Figure 2 is a bottom plan view.

Figure 3 is a sectional view on the line 3-3 of Figure 1.

55 Figure 4 is a sectional view on the line 4-4 of Figure 2.

Figure 5 is a perspective view of one of the clamp sections.

Figure 6 is a view of the wedge members and the spring connecting the same. 60

Referring now to the drawings in detail, the numeral 1 designates the abutting ends of two railway rails. In the present instance, the rail ends are connected by angle plates 2, and the said rail ends rest on ties 3. Between two of the ties 3 the rails are 65 braced and supported by a clamping device in accordance with this invention.

The clamping device includes two similar sections indicated by the numeral 4 respectively. Each section is shaped to provide a base 5, a side 6 which is arranged upon the outer edge of the base and an inwardly directed portion in the nature of a jaw 7. The jaws 7 are shaped so that their lower 70 portions will contact with the horizontal flanges of the angle plates and their inner ends will contact with the vertical faces of the said angle plates. The base portions 75 of the clamp sections are disposed a considerable distance below the base or bottom portions of the rails, and the said base portions are preferably notched or slotted, as at 8 from their inner to adjacent their outer ends. The outer face of each clamp section 80 has an aligning opening therethrough, and through these openings there is passed a bolt 9. The bolt is threaded at both of its ends and its said threaded ends are engaged by nuts 10. Preferably the openings through 85 which the bolts pass are somewhat vertically elongated to permit of the canting of the clamp sections thereon.

The base 5 of each of the clamp sections 4, at the inner end thereof is channeled or 90 grooved from its outer to its inner end, the said grooves or channels being indicated by the numeral 11, and resting on the walls of the said channels there are wedge members 12. As disclosed by the drawings, the wedge 100 members have their under faces rounded, as at 13, and their upper faces flat. The inner and widened ends of the wedge members are each provided with an aperture 14 within which is received the angle extensions or 105 fingers 15 provided upon the parallel members 16 of springs. The parallel members or arms of the springs are coiled, as at 17 upon their outer ends, and the springs are held in proper position by the arrangement 110 of the bolt 9 therebeneath.

The nuts 10 on the bolt 9 are not nec-

sarily screwed entirely home. The spring is of sufficient strength to at all times exert a pressure upon the wedge members to force the same away from each other and consequently to cause the lower rounded and beveled faces thereof to travel in the concaved depression in the base portions of the clamp sections, so that the upper flat faces of the said wedge members will be brought into frictional engagement with the lower foot or bottom portions of the rails. Such movement of the wedges will have the effect of canting or tilting the clamp sections so that the jaw portions thereof will be brought into tight engagement with the side and base of the angle plates, or into engagement with the web and base flange of the rails were the angle plates not employed.

It is thought that the foregoing description, when taken in connection with the drawings will fully set forth the construction and advantages of the improvement and that further detailed description will not be necessary.

25 The bolts have arranged thereon split lock washers 18, one of the sides of which being contacted by the nuts and the other sides being forced into engagement with the clamp sections.

30 Having described the invention, I claim:—

1. In combination with the abutting ends of two railway rails and angle plates connecting the rails; of a clamp comprising two sections constructed to engage the angle plates arranged beneath the bottom of the rails, at the meeting ends of the said rails, means connecting the clamp sections below the rails, and spring influenced wedge members between the clamp sections and the bottom of the rails.

2. In combination with the abutting ends

of two railway rails, and angle plates connecting the rails; of a clamp comprising two sections, each of said sections including a base, a side and a jaw formed on the side, 45 said jaw designed to contact with the horizontal and vertical flanges of the angle plates, means connecting the base portions of the clamp sections, opposed wedge members between the base of the clamp sections 50 and the bottom of the rails, spring means influencing the wedge members away from each other, and the connecting means between the clamp sections supporting said spring means. 55

3. In combination with the abutting ends of two railway rails and angle plates connecting the rails; of a clamp comprising two sections which engage with the rails at the meeting ends thereof, each of said sections 60 comprising a base, a side and a jaw secured to the side, said jaw designed to be arranged on the horizontal flange of the angle plate and to contact with the vertical flange of the said plate, the base of each of the clamp 65 sections being centrally slotted, a bolt member passing through the slots, nuts on the ends of the bolt contacting with the outer face of the clamp sections, said clamp sections having their base portions inclined 70 inwardly from their outer to their slotted ends and having their upper faces depressed from their inner ends, wedge members having lower rounded faces received in the said depressions, spring means between the wedge 75 members influencing the same in an outward direction with respect to each other, and the said bolt underlying and supporting the said spring means.

In testimony whereof I affix my signature. 80

DAVIS AMBROSE.
